UNITED STATES PATENT OFFICE.

AUGUSTUS GOODMAN, EDWIN GOODMAN, AND DAVID COWEN, OF NEW YORK, N. Y.,
ASSIGNORS TO A. GOODMAN & SONS, A CORPORATION OF NEW YORK.

MEASURING-MACHINE.

1,139,269.

Specification of Letters Patent. Patented May 11, 1915.

Application filed March 30, 1914. Serial No. 828,419.

To all whom it may concern:

Be it known that we, AUGUSTUS GOODMAN, EDWIN GOODMAN, and DAVID COWEN, citizens of the United States, residing at New York, 5 city, in the county of New York and State of New York, have invented certain new and useful Improvements in Measuring-Machines; and we do hereby declare the following to be a full, clear, and exact description 10 of the invention, such as will enable others skilled in the art to which it appertains to make and use the same.

This invention relates to measuring machines and has for an object to provide a device 15 for filling a plurality of bags, cartons, or other containers at simultaneous operation with predetermined equal quantities of a powdered, granular or similar material.

A further object of the invention is to provide 20 a device having a plurality of chutes communicating with a hopper or other receptacle, such chutes being adjustable as to length to vary their capacity, with improved means for cutting off communication between 25 such chutes and the hopper and improved means for discharging the contents into the receptacles.

A further object of the invention is to provide 30 improved means for adjusting the capacity of the chutes to receive and discharge predetermined quantities of material.

With these and other objects in view the invention comprises certain novel constructions, combinations and arrangement of 35 parts as will be hereinafter more fully described and claimed.

In the drawings: Figure 1 is a view partly in side elevation, and partly in section of the device. Fig. 2 is a top plan view 40 of the device showing the hopper in section taken on line 2—2 of Fig. 1. Figs. 3 and 4 are sections taken respectively on line 3—4 of Fig. 2, showing the discharging and retaining means respectively open and closed.

45 Like characters of reference designate corresponding parts throughout the several views.

The improved measuring machine which forms the subject matter of this application 50 comprises a hopper or container 10 of any approved form and capacity and supported in any approved manner. In the bottom of the hopper a flooring 11 is provided having a plurality of holes formed therein and 55 tubes 12 secured therein and extending be-

low such flooring. Below the flooring 11 frame or base 13 is provided and a slide 14 is mounted to move in such frame or base abutting the lower ends of the tubes 12. The slide 14 is provided with openings 15 60 adapted to at times register with the lower ends of the tubes 12, as indicated more particularly at Fig. 3 and at other times to be out of registry and close the ends of such tubes as indicated at Figs. 1 and 4. Secured 65 also to the frame or base 13 are tubes 16 forming part of the chutes and in registry with the tubes 12 so that when the slide 14 is moved with the holes 15 in registry with the tubes 12 there is a continuous passage from 70 the hopper 10 through the tubes 12 and 16.

To the sides of the hopper 10 brackets 17 are secured with a frame 18 slidably mounted upon such brackets, the position being controlled by winged nuts 19. The 75 frame 18 also carries tubes 20 telescoping with the tubes 16 and forming therewith chutes which are closed by the slide 21 sliding in the frame 18 as the slide 14 slides in the cleats 13. The slide 21 is provided with 80 openings 22 proportioned at times to register with tubes 20 as shown particularly at Fig. 4 and at times close such tubes as indicated at Figs. 1 and 3. Below the slide 21 discharge spouts 23 are positioned so that 85 material discharged from the chutes through the slide 21 passes through the discharge spouts 23.

Beneath the discharge spouts 23 a receiving frame 24 is provided holding a plurality 90 of bags, cartons or other containers 25 in properly spaced position to receive material from the spouts 23 as indicated more particularly at Fig. 1.

The cleats 13 carry scales 26 with pointers 95 27 carried by the frame 18 so that the exact position of the frame 18 may be once determined and afterward secured by adjusting the four corners of the frame 18 to register with the predetermined markings upon 100 the scale 26.

In operation it is obvious that material contained in the hopper 10 as shown at Fig. 1 will pass downwardly through the tubes 12 until meeting the slide 14. When this 105 slide 14 is open to the position shown at Fig. 3 the material will pass down into the chutes until it engages the slide 21 and completely fills the chutes. The slide 14 being then closed confines within the chutes a predeter- 110

mined quantity of the material and when the slide 21 is open such predetermined quantity will be discharged through the slide 21 and through the discharge spouts 23 into 5 the containers 25 disposed in proper position beneath. By this arrangement predetermined quantities of the material may be rapidly measured and discharged into spaced containers so that an entire frame of 10 containers is filled at one operation of the measuring device.

While the device has been shown in the drawing to contain twenty elements, it is to be understood that the number of elements 15 is in no way restricted to such number shown and may be either more or less as circumstances may make necessary or desirable.

We claim:

20 In a measuring device, a container, tubes extending downwardly therefrom, a base portion provided with apertures through which said tubes project, the base projecting laterally from the sides of the container, a plurality of hangers secured to the con-

tainer and having threaded portions at one 25 end, the upper end of each hanger being provided with an offset portion whereby the threaded portion projects laterally from the base of the container, a frame adapted to be carried below the container, tubes mounted within said frame and arranged to telescope with the tubes first mentioned, brackets carried by the frame and projecting laterally therefrom, said brackets being disposed immediately below the offset portions 30 of the hangers, nuts carried by the hangers and engaging the brackets, a slide provided with apertures, said slide being carried by the frame, and a second apertured slide 35 carried by the base of the container. 40

In testimony whereof we affix our signatures in presence of two witnesses.

AUGUSTUS GOODMAN.
EDWIN GOODMAN.
DAVID COWEN.
